DESIGN FOR A WINDOW CURTAIN TIE-BACK

Ethel P. Brewer, Wayne, N. J.

Application May 29, 1933. Serial No. 48,238

Term of patent 3½ years

To all whom it may concern:

Be it known that I, (MRS. JOHN E.) ETHEL P. BREWER, a citizen of the United States, and a resident of Wayne, in the county of Passaic and State of New Jersey, have invented a new, original, and ornamental Design for a Window Curtain Tie-Back, of which the following is a specification, reference being had to the accompanying drawing, forming part thereof.

I claim:

The ornamental design for a window curtain tie-back, as shown.

ETHEL P. BREWER.
